UNITED STATES PATENT OFFICE.

JAMES T. CURRAN, OF CHICAGO, ILLINOIS, ASSIGNOR TO LUCINDA ELIZABETH CURRAN, OF CHICAGO, ILLINOIS.

COMBINED DUSTPAN AND BROOM HOLDER.

Application filed January 13, 1927. Serial No. 160,946.

This invention relates to improvements in combined dust pans and broom holders, and has for one of its objects to provide a very simply constructed device of this character which, while it can be very inexpensively manufactured, will be very efficient in operation.

An additional object of this invention is to provide a dust pan which can be readily moved around to various places by the foot of the user.

A still further object of the invention is to provide a dust pan having an improved foot piece whereby the pan may be securely held in contact with the floor when the same is in use.

With these and minor objects in view, my invention resides in the novel features of construction which will be hereinafter more particularly set forth in the specification and claims.

In the accompanying drawings:

Figure 1 represents a side elevation of the head of a broom, showing the same held in my combination dust pan and broom holder;

Fig. 2 is a perspective view of the device;

Fig. 3 is a vertical longitudinal section showing the device used as a dust pan.

Fig. 4 is a bottom plan view.

In its preferred form, my invention comprises a dust pan formed from a single piece of sheet metal and having an improved foot piece on the rear end thereof. The dust pan proper is formed from a bottom plate 1 whose front edge is adapted to contact with the floor while its rear edge is spaced a considerable distance above the same. At a point a short distance from the front edge of the plate 1, the same is provided with a transverse depression 2, thus offsetting the rear portion of the plate and causing it to be disposed in a plane below the plane of the front portion. This arrangement provides a receptacle for holding the dust and dirt which is swept into the pan and thereby preventing the same from sliding from the pan when moved from place to place. This offset portion extends from the opposite sides 3 of the pan as shown in Fig. 2 and also serves as a stop to limit downward springing of the body of the pan.

These sides 3 extend from the front to the rear edges of the plate 1 and are preferably inclined from said front to the rear

edges, and the rear portions are curved inwardly so as to overhang the plate 1 as shown at 4. As the plate 1 is tapered from its front to its rear end and has the curved overhanging sides 4 as just described, it is obvious that the head 5 of a broom will be effectively held in said pan when the same is disposed with its front end upwardly. In placing the broom in the holder, the head 5 is held above said holder and allowed to slide downwardly between the sides 3. This downward movement will continue until said head is wedged between the converging curved sides of the device.

In order that the rear end of the device may be spaced above the floor when the same is used, I provide an upwardly and forwardly inclined foot plate 6 which has its front edge bent laterally as shown in Fig. 3, the lateral bent portion 7 forming an attaching flange by which the foot piece may be soldered or riveted to the underside of the dust pan. The rear edge has a cylindrical roll 8 formed thereon, the bottom of said roll being adapted to contact with the floor. As shown in Fig. 3, the only points of contact of the dust pan with the floor, are the front edge of the bottom plate 1 and the bottom side of this roll 8. Therefore, it is evident that if the foot plate 6 is forced downwardly, the front edge of the bottom plate 1 will also tend to move in this direction and will be maintained in close engagement with the floor. Any undue pressure on the plate 6 which might tend to bend the pan is stopped by the engagement of the offset or depressed portion 2 with the floor. When the foot of the user is placed on the plate 6, it is shoved forward until the toe contacts with the bottom of the plate 1, thus somewhat more than half the length of the foot is disposed beneath the dust pan. The foot is thereby wedged between the plates 1 and 6 and the pan can be readily carried from place to place on the foot until the pan is forcibly disengaged. The roll 8 which extends above the upper edge of the plate 6 prevents the shoe from readily coming out of engagement with the plate 6 as will be readily evident without further description.

Uprights 9 connect the rear edge of the plate 6 and the rear edge of the dust pan. The upper ends of these uprights are bent laterally as shown at 10 to provide attaching

members by which the same may be secured with the underside of the dust pan. The lower ends of these uprights 9 are, however, preferably formed integrally with the bottom plate and are placed at the opposite ends of the roll 8. This roll is also preferably formed integrally with the bottom plate 6. These uprights not only support the dust pan but also prevent lateral shifting of the user's foot on the plate 6 as they are disposed on opposite sides of the foot.

In the use of this device, it is seldom necessary when employing it as a dust pan, for the user to move it about with the hands, as the foot when placed between the uprights 9 and on the plate 6 can be readily used for moving it from place to place. The pan can be moved considerable distances while it is on the user's foot. When being moved thusly from place to place, there is no danger of the dirt contained in the pan front sliding therefrom as this is prevented by the depression in the bottom plate of the pan. After the owner of the device is through using the same as a dust pan, the dirt therein is emptied, and the broom used for sweeping up the dirt into the pan is placed therein as heretofore described. The device with the broom can now be hung up on a suitable nail or other hanger by inserting the same in the hole 11 formed in the foot plate 6.

From the foregoing description of the construction and the use of my improved combination dust pan and broom holder, it is obvious that I have produced an extremely simple yet very efficient device of this character. I desire to emphasize the fact that

by pressing downwardly on the plate 6, the front end of the plate 1 of the pan is held in contact with the floor so that the sweepings will go into the pan and not beneath it.

I claim as my invention:

1. A combined dust pan and broom holder open at its front and rear ends and comprising a bottom and upstanding side walls along the side edges of the bottom, said side walls having the upper edges of their rear portions turned inwardly and spaced from the bottom of the pan, said bottom having its front edge engaged with the floor and having a transverse downwardly offset portion a short distance from its front edge, said offset portion forming a dust receptacle and serving as a stop to limit the downward springing of the pan body and an upwardly inclined foot plate attached at its forward edge to the bottom of the pan and having its rear edge in contact with the floor whereby when engaged by the foot said plate will be forced downwardly and the front end of the pan held in engagement with the floor.

2. A structure as specified in claim 1; said foot plate having on its forward edge a laterally bent flange for attachment to the bottom of the pan and having on its rear edge a cylindrical roll for engagement with the floor, and uprights on said rear edge of the foot plate at the ends of said roll, the upper ends of said uprights being secured to the under side of the dust pan.

In testimony whereof I have hereunto affixed my signature.

JAMES T. CURRAN.
